N. ISACHSON.
TIMER ATTACHMENT.
APPLICATION FILED FEB. 18, 1919.

1,336,296.

Patented Apr. 6, 1920.

Inventor:

Norman Isachsen,
by Stan Middleton Donaldson Stan
Atty.

UNITED STATES PATENT OFFICE.

NORMAN ISACHSON, OF ALBION, IDAHO.

TIMER ATTACHMENT.

1,336,296.

Specification of Letters Patent.

Patented Apr. 6, 1920.

Application filed February 18, 1919. Serial No. 277,884.

To all whom it may concern:

Be it known that I, NORMAN ISACHSON, a citizen of the United States, and resident of Albion, Idaho, have invented certain new and useful Improvements in Timer Attachments, of which the following is a specification.

My present invention relates to an attachment for timers for internal combustion engines, and aims to provide what I term an extension terminal which is readily applicable to all the timers, such as are customarily used in connection with Ford engines, though applicable to all engines using timers of this type.

My attachment is designed to provide a construction in which all the movements or twisting of the conducting wires is eliminated during advance and retarding of the spark, thus removing the liability of breakage, and in which the wires or conductors are protected from the deleterious action of oil and grease.

The invention includes the novel features of construction and arrangement and combination of parts hereinafter described and defined by the appended claims.

An embodiment of my invention is illustrated in the accompanying drawings, in which,

Figure 1 is a plan view of my improved attachment.

Fig. 2 is an edge view, and,

Fig. 3 is a view showing the attachment as applied to an engine frame and timer which latter, as it forms *per se* no part of the present invention, is not shown in detail.

Figs. 4 and 4^a are detail views of the holding clips.

Referring by reference characters to this drawing the numeral 1 designates the oscillating element, which is rocked in one direction or the other to advance or retard the spark in the manner well understood by those skilled in the art, and 2 the binding posts corresponding in number to the number of cylinders of the engine, four being shown in the present instance, to which 40 binding posts the wires or conductors leading to the spark plugs are connected.

3 designates my extension device or attachment which has a ring-shaped portion 3^a and an extension for body 3^b of suitable length.

The open center of the ring shaped por-

tion is designed to fit around and encircle the cylindrical or circular body 1 of the timer, so as to permit the latter to freely oscillate within said open center, and be held on the head 4 of the engine by two clamping plates or clips 5 and 5^a secured in position by the engine head stud bolts 4^a and 4^b. In the drawing the engine head is represented as that of the Ford engine.

The attachment is provided on one face with a series of annularly arranged arc shaped spring contacts 6 corresponding in number with the number of binding posts, and these spring members 6 are designed to make rubbing contact with the nuts on the binding posts of the timer, it being understood that the distributing wires are disconnected therefrom.

As the distance of the binding posts from the face of the timer vary somewhat with different makes I find it desirable to use a spring contact member having a part doubled back upon the body to provide for greater adjustment while maintaining the contact force in parallelism with the plane of the binding posts, the extremities of the contact faces being curved as shown at 6^a and 6^b.

These contact springs are connected to the body 3 by screws 7 engaging nut members 8, which also serve to connect the ends or terminals of wires or conductors 9 to said spring contacts.

The wires 9, which are insulated from each other, extend longitudinally of the body 3^b to or near the end thereof, where they are connected to binding posts 10, to which the ordinary distributing wires are connected.

I prefer to construct the body 3 of insulating material and preferably also of two or more layers, as indicated at 2 and 3, which may be conveniently secured by folding the strip at 6, the free ends of the layers being secured together by the binding posts 10. This enables me to easily lay the conductors 9 in position, secures complete insulation of the wires, and effectually excludes oil and dirt therefrom, when properly coated.

From the foregoing description it will be readily seen that I provide a very simple and economical attachment which may be readily attached by any unskilled person to the ordinary engine, and which will keep the conductors elevated and protected from oil and dirt and free from the repeated

twisting movement to which they are customarily subjected. It will be further observed that as the contact between the spring members and binding posts of the timer is a rubbing contact good electrical connection will always be assured.

What I claim is:

1. An attachment for multiple cylinder engine timers comprising a ring-shaped member adapted to be secured to the engine casing in proximity to the oscillating member of the timer, a plurality of elongated yielding contact members carried by said member, said contact members being curved on arcs of circles concentric to the axis of said oscillatory member and adapted to make rubbing contact with the binding posts of said oscillating member, and means for connecting the said spring contacts to the engine distributing conductors.
2. An attachment for multi-cylinder engine timers comprising a member formed of two layers of material suitably secured together, said member having a ring shaped portion at one end, a plurality of annularly arranged elongated spring contacts carried by said ring shaped portion, conductors confined between said layers and connected to said spring contacts at one end, and binding posts for the other ends of said conductors.
3. The combination with the cylindrical oscillatory member of a multi-cylinder engine timer having projecting posts, of a member having a ring shaped portion adapted to be slipped over said cylindrical portion, a plurality of spring contacts carried by said ring shaped portion, said contacts being curved on arcs of circles concentric

with the center of said ring and adapted to make rubbing contact with the projecting binding posts, and means for clamping said member to the engine casing.

4. The combination with the cylindrical oscillatory member of a multi-cylinder engine timer having binding posts projecting outwardly from the periphery thereof, of a member having a ring shaped portion encircling said oscillatory member, a plurality of annularly arranged elongated spring contacts carried by said ring shaped portion, said contacts being curved on arcs concentric with said oscillatory member and adapted to make rubbing contact with said binding posts, and conductors connected to said spring contacts.

5. An attachment for engine timers comprising a flat elongated member having a ring shaped portion at one end, a plurality of annularly arranged arc-shaped spring contacts secured to one face of said ring portion, binding posts carried by the other end of said member, and conductors connecting said spring contacts with said binding posts.

6. The combination of the oscillatory member of a multi-cylinder engine timer having radially extending binding posts, of an elongated member having a ring shaped portion to encircle said oscillatory member, a plurality of annularly arranged elongated arc-shaped spring contacts secured to one face of said ring shaped portion and adapted to bear against the sides of said binding posts and conductors carried by said member and connected to said spring contacts.

In testimony whereof, I affix my signature.
NORMAN ISACHSON.
